ALPHA H. METCALF, OF ATTLEBORO, MASSACHUSETTS, ASSIGNOR TO HORTON ANGELL CO., OF ATTLEBORO, MASSACHUSETTS, A CORPORATION OF MASSACHUSETTS.

CUFF-BUTTON.

1,180,731.

Specification of Letters Patent. Patented Apr. 25, 1916.

Application filed September 15, 1915. Serial No. 50,879.

To all whom it may concern:

Be it known that I, ALPHA H. METCALF, a citizen of the United States, residing at Attleboro, in the county of Bristol and State 5 of Massachusetts, have invented a new and useful Improvement in Cuff-Buttons, of which the following is a specification.

This invention relates to certain new and useful improvements in cuff buttons and pertains more especially to cuff buttons for use 10 with soft cuffs.

The primary object of the invention is to provide cuff buttons which will eliminate the danger of loss, which latter is common to 15 soft cuffs due to the fact that the cuffs being unstarched and readily pliable ineffectively grip the buttons and consequently loss is frequent.

A further object of the invention is to 20 provide cuff buttons formed of two parts which may be easily and quickly connected, and to also generally simplify and improve the structure of the buttons.

In the drawings Figure 1 is an elevation 25 of a button constructed in accordance with the present invention. Fig. 2 is an enlarged elevation, partly broken away and in section. Fig. 3 is a detail sectional view, and Figs. 4 and 5 are top plan views of the male 30 and female parts which form the connection.

The button is formed of two parts 1 and 2 which latter have the usual ornamental outer 35 heads 3 and 3' and shanks 4 and 5, the part 1 constituting what will be termed the male member and the part 2 the female member. The shank 4 is formed with an integral inner 40 head 6 which has a curled or curved flange 7 the free edge of which is spaced from the peripheral part of the flange, as shown in Figs. 2 and 3 so as to permit the free edge to give as indicated in dotted lines in Fig. 3. The inner heads of the two members are of circular outline for a reason later set forth. 45 The male member also has its shank 5 formed with an inner head 8 the peripheral edge of which is rolled over to form an annular bead 9. It will be understood that the flange 7 is of resilient nature or possessed of

resilient properties, so that when the bead 50 9 is forced against the flange 7 from the interior of the latter, the flange 7 will slightly give, as shown in Fig. 3, the give depicted in the latter figure being slightly exaggerated so as to more clearly illustrate the action. In brief, the circular head or male member snaps into the socket which is also of circular formation provided by the flange 7 of the female member.

In operation, the inner heads are forced 60 through the respective buttonholes of the cuff whereupon the inner heads are snapped into engagement which thus disposes said heads in the space between the cuff sides as illustrated in Fig. 1, the two heads thus 65 forming, in conjunction with each other a central head between the ornamental heads. This central head limits the lateral movement of the button relative to the cuff and in addition by reason of the comparatively 70 large diameter of the central head prevents accidental disengagement of the button from the cuff. The inner heads fit with sufficient frictional contact so as to hold the same 75 against relative rotation.

Having thus described my invention, what I claim as new and desire to secure by Letters Patent is—

1. In a cuff button, a pair of members each having an outer head, and a tubular shank 80 having its inner end extending outwardly at right angles to constitute flat disks adapted to lie between the inner side faces of a cuff, the peripheral edges of the disks being rolled toward each other to form respectively 85 male and female parts of a separable connection, the male part being entirely received by the female part to provide a single enlargement between the side faces of the cuff, the opposite faces of the enlargement 90 being defined by the disks which are retained spaced apart by the rolled edge of the male part abutting the female part.

2. In a cuff button, a pair of members each having an outer head, a shank and an 95 inner head, one of said inner heads constituting the male part and the other inner head the female part of a separable fas-

tener, each inner head being in the form of a disk-like body having its peripheral edge rolled inwardly, the rolled edge of the female inner head entirely receiving the rolled edge of the male head, and abutting the disk-like body thereof.

In testimony whereof I have subscribed

my name to specification in the presence of two subscribing witnesses.

ALPHA H. METCALF.
